United States Patent Office

Des. 200,756
Patented Apr. 6, 1965

200,756

GLOVE

Donald F. Rowley, 131 Parkwood Drive, and Donald E. Lowe, 321 Samaritan Ave., both of Ashland, Ohio

Filed July 22, 1963, Ser. No. 75,919

Term of patent 14 years

(Cl. D3—11)

FIG. 1

FIG. 2

FIG. 4

FIG. 3

FIG. 5

FIG. 6

FIG. 7

FIGURE 1 is a front elevation of a glove embodying our design;

FIGURE 2 is a rear elevation of the glove of FIGURE 1;

FIGURE 3 is an enlarged elevation of a portion of the palm of the glove of FIGURE 1;

FIGURE 4 is an enlarged section of the glove taken on line 4—4 of FIGURE 3;

FIGURE 5 is a right side elevation of the glove of FIGURE 1; and

FIGURES 6 and 7 are enlarged sections on lines 6—6 and 7—7 of FIGURE 2, respectively.

We claim:

The ornamental design for a glove, as shown.
